CLAIM

The ornamental design for a charging box for wireless earphones, as shown and described.

DESCRIPTION

FIG. 1 is a front, right, and top perspective view of a charging box for wireless earphones, showing my design. FIG. 2 is a rear, left, and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, left, and top perspective view of a charging box for wireless earphones, wherein a lid is open. The broken lines shown in the drawings depict portions of the charging box for wireless earphones that form no part of the claimed design.
